CLAIM

The ornamental design for a hinge for furniture, as shown and described.

DESCRIPTION

FIG. 1 is a perspective view of the front, left and bottom of a hinge for furniture showing my new design;

FIG. 2 is a front view thereof;

FIG. 3 is a top plan view thereof;

FIG. 4 is a bottom view thereof;

FIG. 5 is a left side view thereof;

FIG. 6 is a right side view thereof;

FIG. 7 is an enlarged left side view thereof;

FIG. 8 is an enlarged right side view thereof; and,

FIG. 9 is a reference view of usage thereof.

The elements shown in broken lines are for illustrative purposes only and form no part of the claimed design.
